UNITED STATES PATENT OFFICE.

LOUIS A. HUESCHMIDT, OF SAN FRANCISCO, CALIFORNIA.

INSULATING-CANOPY FOR LIGHTING-FIXTURES.

1,277,934.

Specification of Letters Patent. Patented Sept. 3, 1918.

Application filed February 13, 1918. Serial No. 216,936.

To all whom it may concern:

Be it known that I, LOUIS A. HUESCHMIDT, a citizen of the United States, residing at the city and county of San Francisco and 5 State of California, have invented new and useful Improvements in Insulating-Cano-
pies for Lighting-Fixtures, of which the following is a specification.

This invention relates to an improved 10 ceiling or similar canopy and means for connecting therewith indirect lighting fixtures, chandeliers, or other fixtures which are designed to be supported from or in relation to said canopy.

15 It consists in the formation of a canopy of approved artistic construction, preferably of an insulating material, and means to secure it in place with relation to the fixed junction box, and means formed or 20 connected integrally with the canopy for the suspension of an indirect lighting bowl or equivalent fixture, to be suspended at some distance below the ceiling and canopy.

It also comprises details of construction 25 which will be more fully explained by reference to the accompanying drawings, in which—

Figure 1 is a sectional view of the canopy showing the attachments.

30 Fig. 2 is a view of the canopy, the bowl and suspending attachments.

I prefer to form my canopy of some insulating material, but it may manifestly be made of any material suitable for the purpose and of any desired artistic form as 35 shown.

The canopy, as here shown, comprises an extended base A adapted to rest and fit against the ceiling or other surface to which 40 it is to be applied and in the center it is extended outward to form a pear-shaped or other extension A'. This structure forms a hollow shell which is applied to the ceiling or other surface, and may be secured by 45 bolts 2 extending vertically up through the canopy and having the upper screw-threaded ends engaging the junction box 3, which is shown as fixed within the surface to which the canopy is attached. Through 50 the rounded lower part of the extensions of

bulb A' holes 4 are made for the passage of the electric conductors 5 which enter the junction box and pass downward therefrom to the lighting fixture or bowl 6. This is designed to be suspended by rods, chains, or 55 other suspending devices 7 from the canopy, and in order to make the proper attachment the canopy has formed with or attached to it lugs or projections 8.

These lugs are as many in number as the 60 number of suspending devices 7, as three, four or five. These may be molded and formed integral with the bulb A' when of insulating material, or otherwise fixed when the canopy is of metal or other ma- 65 terial. The rods, cords or chains 7 are pro-
vided with hooks or other means by which these may be attached to the lugs, which are perforated for the purpose, and similarly to the rim of the bowl or other lighting de- 70 vice, which may thus be suspended at any desired distance below the canopy.

Having thus described my invention, 75 what I claim and desire to secure by Letters Patent is—

1. In an electric lighting fixture, in combination with the ceiling junction box having an opening in its bottom, a hollow canopy having a top and a central extension projection downwardly from the top, said extension being hollow and in register with the opening in the bottom of the junction box, screws extending from the top and connected to the bottom of the junction box to support the canopy, and lugs on the extension periphery extending axially of the extension and having openings between their ends to receive suspension chains for the bowl or the like, said extension having openings to one side of the ears to receive the electric light wires so that the latter will extend from the junction box through the hollow extension and through the lug openings to the chains. 85

2. In an electric lighting fixture, in combination with the ceiling junction box, a canopy having a top and a central hollow extension projecting downwardly from the top, fastening means for securing the canopy top to the bottom of the junction 90 box, and a hollow extension having openings to one side of the ears to receive the electric light wires so that the latter will extend from the junction box through the hollow extension and through the lug openings to the chains. 95

100

box, and lugs on the extension periphery formed to engage the bowl chains to suspend the bowl from the canopy, said extension having holes adjacent the lugs to receive the 5 electric light wires so that the latter will extend from the junction box through the hollow extension and through the extension holes to engage the chains.

In testimony whereof I have hereunto set my hand in the presence of two subscribing 10 witnesses.

LOUIS A. HUFSCHEIDT.
